RAILWAY SWITCH LOCK

William C. McWhirter, Wilkinsburg, Pa., assignor to The Union Switch and Signal Company, Swissvale, Pa., a corporation of Pennsylvania

Application August 27, 1946, Serial No. 693,221

3 Claims. (Cl. 246—146)

1

My invention relates to railway switch locks, and particularly to railway switch locks of the type having circuit controlling contacts which may be utilized in the control of either or both the lock and signaling circuits associated with the track switch governed by such a lock.

It has been proposed heretofore to provide a railway switch lock with an manually operable locking plunger which cooperates with a lock rod attached to the points of a railway track switch for locking the points against movement, and which locking plunger is provided with lock means effective at times to prevent operation of the plunger away from a locking engagement with the lock rod. In the usual construction the switch lock is provided with one or more contacts which become operated automatically upon an action of a trainman preliminary to an operation of the locking plunger. For example, such contacts may be operated by a push rod actuated by a door which must be opened to give access to the locking plunger, so that upon a trainman opening the door of the switch lock, the door-controlled contacts are operated to govern circuits including such contacts. A switch lock of this construction is shown, for example, in a copending application for Letters Patent of the United States, Serial No. 644,338, now Patent No. 2,437,328, dated March 9, 1948, filed jointly by me and Glen V. Jefferson on January 30, 1946, for Electric switch locks.

In order to assure that proper sequence of operation of contacts will be obtained automatically, it is sometimes necessary in railway signaling circuits to utilize preliminarily operated contacts of a switch lock in circuits for the control of signals, etc., thereby effecting such controls immediately upon the occurrence of the preliminary action. Where contacts of a switch lock are of the door-controlled type, operation of the contacts and consequent control of the governed circuits are effected automatically by opening the door even though it may be desirable to postpone or even avoid the necessity of effecting such controls.

It is an object of my invention to provide a railway switch lock arranged so as to obtain proper operation of contacts in a predetermined sequence automatically by a trainman in the course of operation of the locking plunger of the switch lock.

Another object is to obtain preliminary operation of contacts by means which requires a positive action of a trainman and which action constitutes a part of the complete action required

2

to unlock the switch after access to the lock has been obtained.

Another object is to provide a railway switch lock incorporating contacts operated during a preliminary portion of travel of a locking plunger and having means for maintaining the locking plunger at its preliminarily operated position during the time required to obtain release of the lock means.

- 10 Another object is to provide means for holding or latching the operating member of a railway switch lock in a preliminarily operated position wherein contacts are governed but release is not effected of the locking imposed by the device.
- 15 The above-mentioned and other important objects and characteristic features of my invention are attained by incorporating into a railway switch lock a contact or contacts operated during a preliminary portion of the operation
- 20 of the handle of the lock to its unlocked position, thereby requiring a positive action of a trainman directed toward obtaining an unlock of the track switch, and means for latching the handle at the preliminarily operated position during the
- 25 interval required to obtain unlocking of the switch lock.

I shall describe two forms of apparatus embodying my invention and shall then point out the novel features thereof in claims.

- 30 In the accompanying drawings, Fig. 1 is a front view of a railway switch lock embodying my invention. Fig. 2 is a vertical sectional view of the lock shown in Fig. 1. Fig. 3 is a rear view of the lock shown in Fig. 1, with certain parts removed or broken away in order better to illustrate the arrangement of the parts. Fig. 4 is a vertical sectional view showing in more detail a portion of the apparatus shown in Fig. 2. Fig. 5 is a front view showing a modification of
- 35 the structure illustrated in Fig. 4. Figs. 6a, 6b and 6c are partial views showing different positional arrangements of the apparatus of Fig. 5. Fig. 7 is a diagrammatic view illustrating the use of the lock embodying my invention in railway signaling circuits. In each of the several views, similar reference characters refer to corresponding parts.

Referring to the drawings, my invention is illustrated applied to a railway switch lock of the type shown in the previously mentioned application, Serial No. 644,338. The switch lock device comprises a casing 10 (see Fig. 1) mounted on the upper end of a support 14 which is secured, as by lag screws 12, to one or more cross ties 13. Supported in a guideway 14 provided

in the lower end of support 11 is a lock rod 15 of the usual type adapted to be secured to the points of a railway track switch (not shown). Rod 15 is provided with an opening or hole 16 which, when the rod occupies a position corresponding to the normal position of the points of the associated switch, aligns with and is adapted to receive a locking plunger 17 pivotally attached to the lower end of an up-and-down rod 18 enclosed within support 11 and pivotally attached at its upper end to a crank 19. This crank is secured to an operating shaft 20 journaled in suitable bearings 21 (see Fig. 2) provided in a supporting frame 22 secured to the bottom of housing 10. A wall 23 divides housing 10 into front and rear compartments 24 and 25, respectively, and shaft 20 mounted in frame 22 disposed in rear compartment 25 projects through an opening 26 into front compartment 24 and has fastened thereto an operating handle 27 provided with a knob 28.

The front compartment 24 is enclosed by a door 29a hinged at one side of housing 10 and when closed is arranged to be locked in the usual manner by a padlock (not shown) which can be operated by the trainman's switch key. The rear compartment 25 is similarly enclosed by a hinged door 29b arranged when closed to be locked by a padlock which may be opened only by a maintainer's key. The doors 29a and 29b each swing outwardly to give access to compartments 24 and 25, respectively. As indicated in Fig. 1, door 29a carries a projection 30 on its inner side for cooperating with and actuating a push rod 31 which extends from compartment 24 through wall 23 into rear compartment 25 for controlling contacts (not shown) in response to an actuation of the rod. A rod 32 also is shown extending from compartment 24 through wall 23 into compartment 25 to provide an emergency release in a suitable manner, such as that explained in the copending application, Serial No. 644,338.

The operating handle 27 has a normal position N (indicated in Fig. 1), in which the handle rests against a stop 33 provided on wall 23. In this position of the handle, plunger rod 17 occupies hole 16 provided in lock rod 15, thereby preventing movement of rod 15 and consequently preventing any movement of the points of the associated track switch. The normal N position of handle 27 therefore corresponds to the locking position of the switch lock. Handle 27 is manually operable to a reverse position R (indicated in Fig. 1) provided an electric lock means hereinafter discussed is energized, and in the reverse position R of handle 27, crank 19 actuated by handle 27 through shaft 20 is operated to a position such that plunger rod 17 is actuated out of engagement with rod 15 to permit movement of the latter rod and of the points of the associated track switch. The reverse position R of handle 27 therefore corresponds to the unlocked position of the switch locking device, and in this reverse position of handle 27 a stop 34 provided on wall 23 engages the handle to arrest its movement. The parts of the lock mechanism are so arranged and proportioned that handle 27 when operated to its reverse position and released, remains in that position against stop 34 until restored to its normal position.

A drum type circuit controller 35 (see Fig. 2) is mounted on shaft 20 for operation by handle 27. The controller is provided with a plurality of contact bands 36 which cooperate with pairs of contact fingers 37a and 37b disposed on opposite sides

of shaft 20 (see Fig. 3) to form circuit controlling contacts governed by the position of shaft 20 and handle 27. The contact bands 36 are secured at their ends within longitudinal slots provided in the insulating drum of the controller, and it follows that by assembling the bands in the proper positions on the drum and by varying their lengths, the contacts 37a-37b can be made to complete or interrupt a contact in any desired position of handle 27. Thus controller 35 may be arranged to govern a plurality of circuit controlling contacts, some of which may be completed in the normal (N) position of handle 27 and opened when the handle is operated away from that position; others of which may be completed only when handle 27 is in or near its reverse (R) position; and still others of which may be completed only when handle 27 is in a position intermediate its normal and reverse positions, as for example when the handle is intermediate the X and Y positions indicated in Fig. 1 and discussed hereinafter. The contact fingers 37a and 37b are secured by means of terminal posts 38 to insulating terminal boards 39 which in turn are supported on supporting bracket 22.

As previously mentioned, the operation of handle 27 from its normal N to its reverse R position can be effected only when an electric lock means provided for the handle is energized. The electric lock means comprises a locking segment 40 formed integrally with crank 19 and provided with a notched or cutaway portion having a shoulder 41 which cooperates with a locking dog 42 secured by a finger 43 (see Fig. 2) to a vertically swinging armature supporting member 44. Member 44 is pivotally supported intermediate its ends by trunnions 46 journaled in trunnion screws 46a screwed through lugs 47a provided on a supporting plate 47 bolted to the upper end of supporting frame 22, and the member 44 carries an armature 48 which cooperates with pole pieces 49 formed on the lower ends of cores 50 of an electromagnet L. The cores 50 are mounted in parallel spaced relation in the supporting plate 47 and are connected together at their upper ends by a backstrap 51. Surrounding the cores are coils 52 which will be connected in circuit so as to create cumulative flux in the cores, and which coils constitute the energizing winding for electromagnet L.

Armature supporting member 44 extends rearwardly past its point of pivotal support and has secured thereto a counterweight 53 which counterbalances the weight of the armature and locking dog 42 so as to enable a reasonable degree of energization of electromagnet L to attract the armature to its energized position, and thereby lift dog 42 out of the path of travel of shoulder 41, as will be pointed out hereinafter. The locking dog 42 is operatively connected by means of a vertical rod 55 (see Figs. 1 and 2) with a pivoted indicator 56 visible through a window 57 in the partition wall 23 of housing 10. The indicator may assume any one of a variety of forms, but as shown comprises a pivoted arcuate member 58 positioned behind window 57 to display locked or unlocked aspects according as locking dog 42 is released into the path of travel of shoulder 41, or is swung upwardly out of the path of the shoulder.

The armature supporting member 44 also is operatively connected by a movable insulating link 60 to movable contact fingers, such as fingers 61 and 62, which cooperate with other fixed contact fingers, such as fingers 63 and 64, to form

circuit controlling contacts 61-63 and 62-64. The contact fingers 61, 62, 63 and 64 are secured by terminal posts 65, 66, 67 and 68, respectively, to insulating terminal board 69 mounted on the rear end of supporting plate 41. As shown, the fingers are disposed so as to complete or interrupt a contact according as armature 48 is in its full released, or is in its picked-up position, respectively, but it is to be understood that where desired the fingers of either or both contacts may be reversed so as to be opened or closed according as armature 48 is released or picked up.

Locking dog 42 is maintained against lateral displacement by a slotted guide member 70 (see Fig. 3) formed integrally with supporting frame 22, and dog 42 is operable from a released position in which it is adapted to be in the path of travel of shoulder 41 of segment 40, to an unlocked position in which it is removed from the path of shoulder 41. The segment 40 is constructed so that with handle 27 in its normal position and armature 48 released, locking dog 42 rests upon the notched or cutaway portion of the segment, and dog 42 rides on the notched portion of segment 40 when handle 27 is operated from its normal position, until shoulder 41 engages dog 42 in the Y position indicated in Fig. 1. In this Y position of handle 27, locking plunger 17 is still effectively engaged by rod 15 so as to prevent movement of that rod, but contacts of controller 35 closed in the normal position of the handle become open, and contacts open in the normal position of the handle become closed when the handle reaches a position, such as X indicated in Fig. 1, in its movement to the Y position. At the Y position of handle 27, the engagement of shoulder 41 with dog 42 prevents further movement of the handle until such time as electromagnet L is energized to attract its armature 48 and thereby actuate dog 42 out of the path of shoulder 41. In accordance with my invention, contacts operated by handle 27 in the preliminary movement of the handle to the Y position are utilized in the control of electromagnet L, as will be made clear hereinafter in connection with the description of Fig. 7, and during the appreciable interval of time required for these circuits to effect energization of the electromagnet L, it is necessary so as not to interrupt the established circuit conditions, to maintain handle 27 in its Y position against the bias to its normal position occasioned by the parts, such as rods 17 and 18, that are supported from crank 19.

The handle 27 is maintained in its Y position, against the bias force urging the handle back to its normal position, by means of a latch or detent means such as shown in Fig. 4. Referring now to Fig. 4, the latch means is shown in the condition obtaining when handle 27 is operated to its Y position. The latch means comprise a ball 71 carried in the hollow body of knob 28 of handle 27 and pressed by a spring 73 against a plate 74 enclosing the opening in the knob. The ball 71 cooperates with and rides on a projection 75, provided on wall 23, in the normal position of handle 27, with the projection 75 proportioned so that when handle 27 is operated to its Y position, ball 71 rides off the projection as represented in Fig. 4 and engages the end of the projection to latch handle 27 in that position during the interval required to complete the energizing circuits for electromagnet L. It follows that until locking dog 42 is actuated out of engagement with shoulder 41 of segment 40, handle 27 is latched

in its Y position by the means illustrated in Fig. 4 and will remain so latched until the locking is released and dog 42 is positioned to permit movement of handle 27 to its reverse position.

5 In operating the handle 27 shown in Fig. 4 from the reverse to the normal position, the ball 71 will be depressed when projection 75 is encountered at the Y position, and this may offer some slight resistance to the movement of the handle, but operation of the handle to its full normal position can readily be made without difficulty. Also, if handle 27 is operated from its 10 normal to its Y position wherein ball 71 latches the handle by engagement with the shoulder of projection 75, the handle may be manually restored to its normal position, if desired, by the trainman exerting on the handle sufficient force to depress spring 73 and thereby force ball 71 to ride up on projection 75 to permit movement of handle 27 to its normal position.

15 Fig. 5 illustrates a modified form of the detent means shown in Fig. 4, while Figs. 6a, 6b and 6c are partial views showing different positional arrangements of the detent means of Fig. 5. The 20 detent means of Fig. 5 provides a directional detent operative to detain handle 27 in its Y position during movement of the lever from its normal to its reverse position but ineffective to restrain movement of the lever in an operation 25 from its reverse to its normal position. Referring to Figs 5, 6a, 6b and 6c, the latching device shown 30 comprises a ratchet dog 80 pivotally mounted in rear compartment 25 on a pin 81 journaled in lugs provided on the rear face of wall 23, the 35 axis of pin 81 being parallel to the wall so that dog 80 projects at right angles through an opening 82 in the wall. As shown in Fig. 6a, in the 40 normal position of dog 80 it rests on the lower edge of opening 82 with the lower side of the 45 dog projecting slightly into the path of a spring-pressed rod 83 mounted in the hollow knob 28. The knob 28 carries a pin 84 which operates in a slot 85 provided in rod 83 to restrict movement of the rod within given limits, while spring 86 50 is disposed in knob 28 between rod 83 and the closed end of the knob to urge rod 83 to its fully extended position wherein it projects outwardly from the knob so as to ride normally on the outer 55 face of wall 23. The opening 82 is provided in wall 23 at the Y position of the handle, and the 60 opening is made such that when handle 27 is operated from its normal to its Y position, rod 83 strikes dog 80 (see Fig. 6b) to rotate it, about its axis, until dog 80 engages a stop lug 87 which 65 prevents further rotation of dog 80. The dog 80 when rotated against stop 87 provides a recess formed by the side of opening 82 and the underside of dog 80 and rod 83 occupies this recess to 70 latch handle 27 against movement toward its normal position. When electromagnet L becomes energized to actuate dog 42 out of engagement with locking segment 40, further operation of handle 27 can be made and in this case rod 83 rides on the underside of dog 80 which as 75 shown is positioned at a slight angle to wall 23. The upper edge of opening 82 is cut away or beveled in such a manner as to permit rotation of dog 80 into engagement with stop 87, and when rod 83 clears dog 80 (see Fig. 6c) the dog is returned, either by gravity or by spring pressure, to its normal position in which the upper end of the dog is substantially flush with the outer surface of wall 23. It follows that when handle 27 is operated from its reverse position to its normal position, the rod 83 rides up the slight angle

provided by dog 80, but the dog is not rotated to provide any recess and as a result operation of the handle is not impeded to any extent other than that necessary to depress rod 83 slightly against its spring 86. It is to be seen that ratchet dog 80 provides a means for obtaining a recess engageable by rod 83 when operating the handle 27 from its normal to its reverse position, but that on return of the handle from its reverse to its normal position the ratchet forms no recess for engaging rod 83 and no latching action is effected.

The operation of a railway switch lock embodying my invention will be best understood in connection with the apparatus shown in Fig. 7. Referring now to Fig. 7, the reference character W designates a track switch diagrammatically illustrated as provided with a switch lock, of the type embodying my present invention and shown in detail in Figs. 1, 2 and 3. The reference character 27 designates the handle of the switch lock, with positions N, X, Y and R of the handle corresponding to the similarly designated positions of handle 27 shown in Fig. 1; the reference character L designates the electromagnet of the switch lock; contacts 61, 62, 63 and 64 correspond to the similarly designated contacts shown in Fig. 3, while the reference characters 90 and 91 indicate contacts controlled by drum controller 35, arranged as indicated in Fig. 7 so that contact 90 is closed or completed in the normal (N) position of handle 27, and contact 91 is closed when handle 27 is in or intermediate its X and Y positions indicated in Fig. 7. The reference character TER designates a time element relay having a front contact 92 closed only at the end of a predetermined length of time after the operating element 93 of the relay is supplied with energy, and with a back checking contact 94 closed only when the relay restores to its normally deenergized condition and is prepared for another timing operation; the reference character TESR designates a stick relay repeating relay TER; the reference character NWPR designates a normal switch repeater relay provided to repeat the position of the associated track switch W; and the reference characters 95 and 96 designate circuit controller elements operated by the circuit controller (not shown) provided for track switch W. Contacts 95 and 96 occupy the positions shown when switch W is in its normal position, and are operated to the dotted positions indicated in Fig. 7 when switch W is reversed. The reference characters B and C designate the opposite terminals of a suitable source of current, such as a battery not shown.

The switch lock usually is provided with means, such as a projection on the inner face of door 29a, which insures that door 29a can be closed and padlocked only when handle 27 occupies its normal position. The handle can be operated to its normal position only in the event that plunger rod 17 engages opening 16 in rod 15, and this is effected only when switch rod 15 occupies a position corresponding to the normal position of switch W. In the normal position of the switch lock, therefore, switch W is locked against movement, handle 27 is in its normal position, and both doors 29a and 29b are closed (as indicated in Fig. 2) and locked by their respective padlocks previously mentioned. Electromagnet L is deenergized; relays TER and TESR of Fig. 7 are likewise deenergized; and relay NWPR is normally energized over a circuit extending from terminal B through back checking contact 94 of relay

TER, back contact 98 of relay TESR, contact 90 of handle 27 closed in the normal (N) position of that handle, contact 61-63 controlled by the armature of electromagnet L of the switch lock, contact 95 closed in the normal position of switch W, the winding of relay NWPR, contact 96 closed in the normal position of switch W, and contact 64-62 of electromagnet L to terminal C. Relay NWPR closes its front contacts, such as contact 100, which may be used in the control of circuits, as indicated in Fig. 7 and as discussed herein-after.

If, with the apparatus in the normal condition just described, it is desired to unlock switch W to enable the switch to be reversed, the padlock controlling door 29a must first be unlocked and removed by the trainman, and door 29a then opened to give access to handle 27. This operation may result in the control of door operated contacts actuated by push rod 31, and these contacts may be utilized for any desired purpose not pertinent to the present invention. However, the opening of door 29a does not result in any control of the electromagnet L or of any of the apparatus shown in Fig. 7, with the result that door 29a can be held open as long as desired, and may even be closed, without effecting any change in the condition of the switch lock and associated apparatus other than possible operation of the door operated contacts.

After access to handle 27 is gained by the trainman opening door 29a, the trainman can then obtain control of switch W by grasping handle 27 and moving it toward its reverse position R. When handle 27 leaves its normal position N, contact 90 is opened to interrupt at that point the previously traced circuit of relay NWPR, and that relay accordingly releases to close its back contact 101 to prepare a circuit for winding 93 of relay TER, which circuit may be traced from terminal B through back contact 102 of relay TESR, the operating element 93 of relay TER, back contact 101 of relay NWPR, and contact 91 of handle 27, closed in or intermediate the X and Y positions of that handle, to terminal C. At the X position of handle 27, contact 91 closes so that relay TER becomes energized over the circuit previously traced, while continued operation of handle 27 to its Y position results in dog 42 engaging shoulder 41 of segment 40 to prevent further movement of the handle. In this Y position, the previously described latching means for the handle becomes effective to maintain the handle in its Y position against the bias of its parts, and the handle may then be released by the operator until the electric unlock is obtained as indicated by indicator 58 visible through window 57 provided in wall 23. The unlock is obtained only after a complete cycle of operation of relay TER, that is, only after front contact 92 closes, and then back contact 94 subsequently closes. Front contact 92 of relay TER closes at the end of a predetermined time interval following the completion of the circuit for operating element 93 of the relay, and completes a circuit from terminal B through front contact 92 of relay TER, the winding of relay TESR, back contact 101 of relay NWPS, and contact 91 of handle 27 to terminal C; whereupon relay TESR picks up to close its front contact 102 and complete for itself an obvious stick circuit in which contact 102 is connected around front contact 92 of relay TER. The opening of back contact 102 of relay TESR interrupts the previously traced circuit of relay TER at that point, and relay TER becomes deenergized and closes its back

checking contact 94 at the end of a predetermined time interval following the deenergization of element 93. When back checking contact 94 of relay TER closes, electromagnet L becomes energized over a circuit from terminal B through back checking contact 94 of relay TER, front contact 98 of relay TESR, and the winding (coils 52 of Fig. 2) of electromagnet L to terminal C. Electromagnet L thereupon attracts its armature 48 (see Fig. 2) to actuate indicator 58 to cause it to indicate the unlocked condition of the electric lock, and opens contacts 61—63 and 62—64, in the manner previously explained. Armature 48 also actuates locking dog 42 out of the path of movement of shoulder 41 of locking segment 40, as explained previously, thereby freeing handle 27 for further movement to its reverse position. This operation of handle 27 to its reverse position usually will be effected immediately by the trainman as soon as indicator 58 indicates unlocked, and in the reverse position of handle 27, plunger rod 17 is operated out of engagement with rod 15 so that the points of switch W are released and the switch is unlocked so that it may be reversed.

From the foregoing description it will be noted that the latching means provided for handle 27 is effective to retain the handle in its Y position during the time required for relay TER to complete the cycle of closing its front contact 92 and subsequently closing its back contact 94. This cycle of operation of relay TER is initiated by operating handle 27 from its normal (N) position into its Y position, and as is customary in switch locking circuits of this type, the time of operation of relay TER may be used to provide a period of warning to traffic approaching on either side of the switch, during which period the switch is locked against operation so as to prevent any possibility of causing a hazardous condition of the switch with reference to approaching traffic. In the system shown in Fig. 7, the contacts operated by relay NWPR may be used to control the warning of the traffic approaching the location of switch W. Relay NWPR, as previously explained, is released upon movement of handle 27 from its normal position and it follows that the warning of traffic is provided automatically by a preliminary operation required of a trainman as a part of the complete operation of handle 27 from its normal to its reverse position, and therefore is initiated only upon a positive act of the trainman indicative of the intention to unlock the track switch. Should the trainman decide not to unlock the switch after gaining access to handle 27 by opening door 29a, then in such event door 29a may be closed without in any way interfering with the circuits governing the warning of traffic adjacent to switch W.

The switch lock apparatus may be restored to its normal position, provided the points of switch W are in their normal positions, by operating handle 27 to its normal position, it being noted that in the event handle 27 is provided with latching means of the type illustrated in Fig. 5, no latching effect will be imposed by these means at the Y position during operation from the reverse to the normal position. With handle 27 restored to normal wherein plunger rod 17 engages rod 15, switch W is locked against operation, while all of the apparatus shown in Fig. 7 will occupy the normal condition as therein illustrated. The door 29a may therefore be closed and padlocked in the customary manner.

An advantage of the apparatus embodying my

invention is the provision of means for latching the operating handle of a railway switch lock at a preliminarily operated position in which the handle initiates the cycle of operation required to obtain an unlock of the track switch. The latching means obviates the necessity of requiring a trainman to hold the handle against the bias of the parts in its preliminarily operated position during the period required to obtain release of the switch lock, and the arrangement is such that a specific and positive action of the trainman directed toward obtaining an unlock of the switch is required before the apparatus imposes any change in the signaling circuits governing traffic approaching the position of the switch.

Although I have herein shown and described only two forms of railway switch locks embodying my invention, it is to be understood that various changes and modifications may be made therein within the scope of the appended claims without departing from the spirit and scope of my invention.

Having thus described my invention, what I claim is:

1. In combination, a casing divided by a partition wall into a front compartment and a rear compartment, a shaft journaled in said partition wall, an operating member in said front compartment operatively connected with said shaft, said operating member having a normal position and an intermediate position and an operated position, means in said rear compartment operatively connected with said shaft adapted to lock the points of a track switch against movement in the normal and intermediate positions but not the operated position of said operating member, a locking dog in said rear compartment operable between a locking position and an unlocking position, means in said rear compartment operatively connected with said shaft cooperating with said locking dog to prevent movement of said operating member from its said normal position past its said intermediate position unless said locking dog is in its said unlocking position, means in said rear compartment for operating said locking dog into its said unlocking position, a time element device operable from a normal to an operated position at the end of a predetermined time interval, means controlled solely by operation of said operating member for setting into operation said time element device, means controlled by said time element device in its said operated position, other means governed by said last mentioned means for controlling said dog operating means to cause operation of said locking dog to its said unlocking position, whereby said operating member may be freed to unlock the switch points following the operation of said time element device initiated by operation of said operating member, an element carried by said operating member biased into engagement with said partition wall, an opening provided in said partition wall, a dog pivotally supported to project into said opening and operable upon engagement by said element to rotate to a position in which said dog and said opening provide a recess engageable by said element at said intermediate position of said operating member, whereby to retain said operating member at said intermediate position during the interval required for said time element device to operate to its said operated position.

2. In combination, a casing divided by a partition wall into a front compartment and a rear

compartment, a shaft journaled in said partition wall, an operating member in said front compartment operatively connected with said shaft, said operating member having a normal position and an intermediate position and an operated position, means in said rear compartment operatively connected with said shaft adapted to lock the points of a track switch against movement in the normal and intermediate positions but not the operated position of said operating member, a locking dog in said rear compartment operable between a locking position and an unlocking position, means in said rear compartment operatively connected with said shaft cooperating with said locking dog to prevent movement of said operating member from its said normal position past its said intermediate position unless said locking dog is in its said unlocking position, means in said rear compartment for operating said locking dog into its said unlocking position, a time element device operable from a normal to an operated position at the end of a predetermined time interval, means controlled solely by operation of said operating member for setting into operation said time element device, means controlled by said time element device in its said operated position, other means governed by said last mentioned means for controlling said dog operating means to cause operation of said locking dog to its said unlocking position, whereby said operating member may be freed to unlock the switch points following the operation of said time element device initiated by operation of said operating member, an element carried by said operating member biased into engagement with said partition wall, and a directional detent for said element comprising an opening provided in said partition wall, a dog pivotally supported on the opposite side of said wall from said element and disposed to project through said opening into the path of said element and rotatable in response to engagement by said element on movement of said operating member from said normal to said operated position but not on movement from said operated position to said normal position.

45

tion, said dog upon rotation forming with the walls of said opening a recess engageable by said element at said intermediate position of said operating member whereby to retain that member in said intermediate position.

3. In an electric switch lock, in combination with a casing provided with a partition wall supporting a shaft provided with an operating member having a normal position and an operated position and an intermediate position, an element carried by said operating member biased into engagement with said partition wall, and a directional detent for said element comprising an opening provided in said partition wall, a dog pivotally supported on the opposite side of said wall from said element and disposed to project through said opening into the path of said element and rotatable in response to engagement by said element on movement of said operating member from said normal to said operated position but not on movement from said operated position to said normal position, said dog upon rotation forming with the walls of said opening a recess engageable by said element at said intermediate position of said operating member whereby to latch that member in said intermediate position to prevent return to said normal position.

30

WILLIAM C. McWHIRTER.
